DES. 2276

Pat. 11-1876. L. M. Daniel Killet, of San Francisco, Cal.

Letters Patent No. 2276. Dated March 6, 1866.

Print or Design for Architectural Center Flowers.

The schedule referred to in the Letters Patent and making part of the same.

In all where it may concern:

Be it known that I, Daniel Killet of the city and county of San Francisco, State of California, have originated and designed a new pattern for "Center Flowers" for buildings etc. of which the following is a full, clear, and exact description referring being had to the accompanying drawing, making part of this Specification in which number 5 I represent a photograph a center piece of my design:

My said Center Flower is composed of plaster of paris, so called, modelled and cast in the usual way, well known to me here in Stucco, with this exception, I prefer to cast the different portions in gelatinous moulds, instead of plaster as by the method or process the design has more of a tone of "high relief" and the parts are brought out with greater distinctness.

My said design consists of a shield or frame composed with fruit and flowers in over of about eight collections, composed of the following, viz: mainly, Apple, Quince, and Pear, with the California Strawberries, attached at the lower end having a bouquet of daisy flowers at the other, or upper end. The other collection consists of bunches of Grapes and leaves with bouquet of daisy flowers placed in high relief on the scroll beneath the Grapes.

Having thus described my design for Center Flowers, what I claim and desire to secure by Letters Patent is the design or pattern for Center Flowers herein set forth.

I do witness in these my hands, in witness and to set my hand and seal this 4th day of January A. D. 1866.
